(57) **CLAIM**

The ornamental design for a laser surveying device, as shown and described.

DESCRIPTION

FIG. 1 is a front, top and right side perspective view of a laser surveying device showing my new design; FIG. 2 is a front, bottom and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is an enlarged front view showing a portion defined by lines 9a-9a' in FIGS. 3 and 9b-9b' in FIG. 5;

FIG. 10 is a cross-sectional view taken along line 10-10 in FIG. 9 with an internal structure partly omitted;

FIG. 11 is a cross-sectional view taken along line 11-11 in FIG. 9 with an internal structure partly omitted;

FIG. 12 is a cross-sectional view taken along line 12-12 in FIG. 9 with an internal structure partly omitted;

FIG. 13 is a cross-sectional view taken along line 13-13 in FIG. 9 with an internal structure partly omitted;

FIG. 14 is an enlarged front view similar to FIG. 9 with a built-in mirror in an upward position;

FIG. 15 is a cross-sectional view taken along line 15-15 in FIG. 14 with an internal structure partly omitted;

FIG. 16 is an enlarged front view similar to FIG. 9 with a built-in mirror in a downward position;

FIG. 17 is a cross-sectional view taken along line 17-17 in FIG. 16 with an internal structure partly omitted;

FIG. 18 is an enlarged front view similar to FIG. 9 with a built-in mirror housing in a position rotated counterclockwise;

FIG. 19 is a cross-sectional view taken along line 19-19 in FIG. 18 with an internal structure partly omitted;

FIG. 20 is an enlarged front view similar to FIG. 9 with a built-in mirror housing in a position rotated clockwise; and,

(Continued)

FIG. 21 is a cross-sectional view taken along line 21-21 in FIG. 20 with an internal structure partly omitted. The evenly-spaced broken lines illustrate portions of the laser surveying device that form no part of the claimed design. The dash-dotted broken lines denote the boundaries of the claim and form no part of the claimed design.

1 Claim, 21 Drawing Sheets
